GARMENT HANGER

Robert L. Fortner, Glendale, and Herbert L. Perrin, Tujunga, Calif., assignors to Fortner and Perrin Inc., Glendale, Calif., a corporation of California

Application April 29, 1949, Serial No. 90,504

3 Claims. (Cl. 223—96)

1

This invention relates to a garment hanger which is especially designed for supporting ladies' skirts, but may also be used for supporting slacks, trousers and other garments.

One of the objects of this invention is the provision of a simply constructed and compact garment hanger which is made from a single length of wire in a particularly efficacious manner to effectively support garments of the type described in various sizes and thicknesses of the portions such as the waist bands and cuffs of slacks or trousers which are clamped and held by the hanger.

Another object is to provide a hanger such as above described in which the construction and arrangement of the parts thereof lends such strength and rigidity that the hanger may be economically made of light and small gauge wire.

Another object is to provide in a hanger such as described, novel clamps formed of portions of the single piece of wire of which the hanger is made and constructed and arranged to depend from the body of the hanger and to be quickly and conveniently operated for clamping and supporting garments over a wide range of sizes and thicknesses of the portions of the garments engaged by the clamps.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a perspective view of a garment hanger made in accordance with our invention;

Fig. 2 is a side elevation of the hanger;

Fig. 3 is an end view of the hanger; and

Fig. 4 is a sectional view taken on the line 4—4 of Fig. 2.

As shown in the accompanying drawing one form of garment hanger embodying the present invention is preferably fabricated from a single length of wire to provide an elongated and substantially straight body portion A, a simple hook B and resilient garment clamps C depending from the ends of the body portion and especially constructed and arranged so that garments of various sizes and thicknesses may be applied thereto in a particularly easy fashion and will be securely held in suspended position subject to removal readily and easily as they may be applied to the hanger.

The body portion A is formed of two substan-

tially straight wire lengths 5 and 6 arranged in opposed side by side relation and spot welded together as at 7 centrally of their ends at which point the shank 8 of the hook B is joined. In the present case the hook is an integral part of the wire portion 5. In this connection it should be noted that the "length" 5 of the wire is in two sections welded together as the point 7 where as length 6 is one continuous part. With reference to Figs. 1 and 2 it will be seen that the hanger is formed so that one end of the single piece of wire is at the free end of the bill of the hook B whereas the other end of said piece abuts and is welded to the shank 8 of the hook at weld joint 7.

From the joint 7 where the wire portions of the body portion A and the hook B are welded together, the two lengths of wire 5 and 6 are extended divergently to their outer ends from which ends the clamps C depend. These clamps are produced from continuous portions of the single piece of wire forming the hanger and comprise like downwardly extended end portions 9 at the ends of the wire lengths 5 and 6 and spaced apart to correspond to said ends, short and similarly spaced inwardly extended portions 10 extending right angularly from the lower ends of the end portions 9, opposed garment clamping portions 11 which extend upwardly from the inner ends of the portions 10, and curved cross portions 12 connecting the upper ends of the clamping portions 11. Thus, the portions 11 and 12 form inverted U-shaped clamps the upper ends (portions 12) of which extend between and slightly above and abut the wire lengths 5 and 6 of the body portion so that the clamps are held against lateral displacement and the clamps as well as entire hanger are given desired rigidity while having free resilient action. The portions 11 are bent inwardly between their ends so as to substantially contact one another and provide closely spaced garment-gripping jaws 14.

The downwardly bent end portions 9 and the upwardly bent clamping portions 11 are in opposed relation and spaced so that they will serve together with the short portions 10 as convenient handle portions in the manipulation of the clamps in the handling of the hanger. The portions 9 also serve as guides for the garment G lying therebetween as seen in Fig. 1. Moreover the portions 9 and 10 serve as levers for springing the clamping portions apart.

Due to the particular formation of the clamps C and the location thereof inwardly of the portions 9, waist bands of garments such as skirts

and trousers of any length may be effectively gripped by the clamping portions 11, as any garment portions of greater length than the hanger will be guided outwardly between the portions 9 and held in place thereby.

Preferably the wire of which the hanger is made is not fully tempered and may be sprung or bent as to the clamping portions 11 and portions 9 to increase the spacing thereof to accommodate garments of different thicknesses and subsequently bent back to more closely spaced relation but will have sufficient resilience to effect a desired clamping action regardless of these adjustments.

Due to the manner in which the parts of the hanger are bent, relatively arranged and interrelated, desired rigidity and strength are provided and adequate spring action of the clamps is had with the use of small gauge wire which need not be tempered to the extent of temper found in the usual spring wire, and in addition, provision is made as hereinbefore noted for adjusting or spreading apart and bending back to normal shape the clamps C to accommodate garments of different thicknesses and sizes.

In the use of the hanger the portion of the garment to be gripped and held can be moved endwise into the clamps C between the opposed end portions 9 and the clamping portion 11 or the garment can be moved upwardly between the portions 11 and 9 or the hanger may be moved downwardly onto the garment. In all cases the garment will be quickly and securely gripped and held due primarily to the formation of the clamp members 11 and their location with respect to the wire lengths 5 and 6 and the end portions 9.

While we have shown and described a specific embodiment of our invention we do not limit ourselves to the exact details of construction set forth, and the invention embraces such changes, modifications and equivalents of the parts and their formation and arrangement as come within the purview of the appended claims.

We claim:

1. In a garment hanger a pair of longitudinally extending spaced wire arms, a hook for suspending the hanger fixed to said arms at a point

substantially centrally of the arm ends, clamps formed from portions of the hanger arms rising upwardly between the opposite sides of the arms adjacent the ends thereof, said clamps opening laterally with respect to the opposite sides of the hanger arms and the hanger arms having portions extending downwardly beyond the clamps, each downwardly extending arm portion being connected to the lower portion of the corresponding side of the clamp.

2. In a garment hanger a pair of longitudinally extending spaced wire arms, a hook for suspending the hanger fixed to said arms at a point substantially centrally of the arm ends, spring clamps integral with the hanger arms rising upwardly between the opposite sides of the hanger ends, the jaws of the clamps opening laterally with respect to the opposite sides of the arms, portions of the hanger arms extending downwardly beyond the clamps and each of said portions having its lower end connected to the lower portion of the corresponding side of the clamp.

3. In a garment hanger a pair of longitudinally extending spaced wire arms, a hook for suspending the hanger fixed to said arms at a point substantially centrally of the arm ends, a single garment clamp at each end of the hanger interposed between the arm ends and having jaws disposed laterally with respect to the opposite sides of the arms, portions of the arms extending beyond the garment clamps, one of which extends downwardly and the other of which extends inwardly therefrom and is connected to the lower portion of the corresponding side of the clamp.
